UNITED STATES PATENT OFFICE.

LEONARD CHARLES BYGRAVE, OF LONDON, ENGLAND, ASSIGNOR TO THE RELAY AUTOMATIC TELEPHONE COMPANY, LIMITED, OF LONDON, ENGLAND.

MEANS FOR CONNECTING ELECTRIC LINES.

1,269,903.

Specification of Letters Patent. Patented June 18, 1918.

Application filed November 22, 1916. Serial No. 132,884.

To all whom it may concern:

Be it known that I, LEONARD CHARLES BYGRAVE, a subject of the King of Great Britain, and a resident of Marconi House, 5 Strand, London, England, have invented a new and useful Improvement in Means for Connecting Electric Lines, of which the following is a specification.

This invention relates to devices for establishing connection between two groups of lines, and more particularly to devices in which the connections are effected by relays.

The drawings illustrate the invention as applied to a relay telephone system.

Figure 1 shows a group of lines X having access to a group of outgoing lines Y.

Fig. 2 shows a group of lines having access to a group of outgoing lines and a group 20 of incoming lines.

Fig. 3 shows a group of lines having access to a larger group of outgoing lines and a larger group of incoming lines.

Fig. 4 shows a modification.

Two wires A and B are shown as connected up by each relay while a third wire R is used for retaining purposes. This is usual in telephone work, but it will be readily understood that any required number 25 of wires can be connected up by each relay. The relays are brought into operation by the two wires A and B being connected together in accordance with standard telephone practice, but any other method 30 could be used.

The lines Y may be multiplied to other relay groups.

Each set of wires A, B and R of the group Y have associated with them another wire 40 G, which is sometimes known as the guarding wire, to prevent a calling line obtaining connection with an engaged line. This is brought about according to this invention by normally having this wire connected to 45 battery and disconnecting it when the line becomes engaged. This method has several advantages over the one generally used, for if a fuse U associated with any line be blown owing to a fault, or if the test wire 50 be broken for any reason, then that line is rendered inaccessible.

The operation of the circuit shown will now be described in detail. It will be assumed that the line L¹ has to be connected 55 to a free line of the group Y, the first line

O¹ being assumed engaged from another relay group and a relay T¹ associated with it being therefore energized. On the wires A and B (L¹) being joined together by the caller lifting his receiver or the like, circuit 1 is completed and the line relay D¹ operates. Circuit 2 is completed and relay F operates. This connects the G wires of all the Y lines to which the group has access to the connection-determining relays M. 60 The M relays therefore of disengaged lines will operate; those of busy lines will not since the negative potential will have been removed from their G wires by the operation of their T relay. M¹ will therefore not 65 be operative, but both M² and M³ operate as O² and O³ are both disengaged (circuits 3 and 4). M² operating opens the circuits to the springs of M³ and thereby renders the operation of the latter ineffective, and only 70 circuit 5 of one connecting relay, viz., C¹², is completed. The latter extends the wires of A and B (L¹) to the line O² and T² operates (circuit 6). Circuit 3 is now broken, rendering the line O² inaccessible to any further calling lines, and the retaining circuit 75 7 is completed operating the cut-off relay E¹. This releases relays D¹ and F. The connection between the line L¹ and O² is maintained so long as the wires A and B are connected together. 80 85

If the relay group is used in connection with an automatic telephone system in which the desired connection is built up by breaking the connection between the wires A and B a certain number of times, T² is 90 made slow to release and is operated indirectly from the wires A and B in a well known manner.

Fig. 2 shows one method of applying the 95 invention to a relay arrangement in which intermediate lines are used to give access to two groups of lines, one of which may be used for outgoing and the other for incoming traffic.

The lines X are particular to the relay group, but the outgoing lines Y and the incoming lines Z may be multiplied to any number of relay groups.

The operation will first be described when 105 a line of group X, say L², obtains connection with a free line of group Y. When the wires A and B (L²) are connected together by the lifting of a receiver or the like, circuit 1 is completed and D² operates. F 110

operates (circuit 2) and connects the G wires of the Y lines to the corresponding M relays, over one winding of the OC relays and break contacts of the IC relays. The latter contacts prevent the M relays energizing if the corresponding intermediate line is engaged for an incoming connection. As the G wires of free lines only are connected to battery, an M relay can only energize when the intermediate and outgoing lines associated with it are both free. Instead of allowing all the M relays corresponding to disengaged intermediate and outgoing lines to operate and to render only the first one effective (as was shown in Fig. 1) only the first M relay is allowed to operate completely owing to each M relay breaking the circuit of all the M relays above it. By this means the number of contacts on the M relays is reduced. It will be seen therefore that only the M relay of the first level with both a free intermediate line and a free outgoing line will operate. For instance, if the outgoing line O¹ be engaged, M¹ will not be able to operate as battery will not be connected to the corresponding G wire. If the second outgoing line O² be free, but the corresponding intermediate line be engaged instead (in which case the relay IC² will be energized) the circuit for M² will be broken by IC². If the third outgoing line O³ and the corresponding intermediate line are both free, then M³ will operate over circuit 3, and prevent the operation of M⁴ by cutting off the common earth. Circuit 4 is completed and C²³ operates. The lines A and B (L²) are extended to O³ and apparatus associated with the latter (similar to the T relays of Fig. 1) disconnects the negative battery from the G wire and completes the retaining circuit 5 and E² operates releasing D² and F.

For an incoming call a similar series of operations takes place. In this case the apparatus is not brought into operation by an X line calling, for the line is being called by a Z line. A numerical selector or other means, not shown, is used to determine the line to be called and operates the J relay of the group to which the line belongs, and at the same time connects battery to the N wire of the required line. For instance, if L¹ is to be called, J would be operated and N (L¹) connected to battery. The M relay, say M¹, of the first level which has both a free intermediate line and a free incoming line, operates. The connecting relay C¹¹ operates, and apparatus associated with the incoming line I¹ disconnects negative battery from the J wire and operates E¹. J is released from the selecting apparatus or in any other suitable manner. The wire H, which is earthed by the M relay, can be used to operate apparatus, for instance, a relay

associated with the corresponding incoming line, to connect such line to the line from which the numerical selector has been operated.

One method of applying this invention to a relay arrangement is shown in Fig. 3. In this diagram only two lines of the X group and two intermediate lines are shown, though any suitable number may be used. Two outgoing (Y) and two incoming (Z) lines are shown as associated with each intermediate line though the number need not be two. The connection of the line L¹ to the first free outgoing line will now be described. On the lines A and B being connected D¹ operates over circuit 1 and F over circuit 2. If both the intermediate line and the first outgoing line O¹ are free M¹ and OC¹ operate over circuit 3. If the intermediate line had been engaged incoming, this circuit would have been broken by IC¹ or IC². The operation of OC¹ prevents the operation of OC² and the operation of M¹ prevents the operation of any other M or OC relays. Circuit 4 is completed and C¹¹ operates. E¹ operates as before described, and D¹ and F¹ release. Similar operations take place when connection between an incoming and a called line is required, as will be readily understood from the description of the operation of Fig. 1.

In the arrangements which have been described no means are provided to prevent double connection. For instance, if the two wires A and B of L¹ are connected together at the same moment as the two wires A and B of L², both these lines will be connected to the same outgoing line. To prevent this a suitable resistance can be inserted in each retaining wire at the point R (Fig. 1). This resistance would be such that in series with it one connecting relay can retain but not two or more relays in parallel. If two lines call concurrently therefore, both connecting relays will not be able to hold, and the one releasing first will release the cut-off E, and the line relay D will re-operate to cause the calling line to be connected to the next free outgoing line.

The resistance used for the arrangements shown in Figs. 2 and 3 would be such that the two connecting relays used for each connection could retain in series with it, but not two or more sets of connecting relays in parallel in series with it.

A similar arrangement could be used for incoming calls.

The invention has been described in connection with systems wherein separate wires are used for retaining and guarding purposes. It can be arranged to use one wire for both purposes, as shown in Fig. 4. The wires R and G are connected in parallel at the point 4¹, and this common wire is extended through the back contact of relay T² 130

to negative of battery at 3^a; for example, if the corresponding line is free. When relay T² is energized, this common circuit is then connected to earth at 3^b; for example, when 5 the retaining circuit is completed. The coils of the E relays are shown connected to negative battery.

The invention is not limited to the relay arrangements or circuits shown, as many 10 modifications can be employed to fulfil other conditions.

What I claim is:—

1. The combination of a group of electrical lines, a second group of lines, a connection-determining device associated with 15 each of the lines of the second group, means for rendering inoperative the connection-determining devices of busy lines and means for rendering operative the connection-de- 20 termining device of one idle line and one only when a connection is to be made and then only.

2. The combination of a group of electrical lines, a second group of lines, a number 25 of connection-determining devices arranged in a definite order of precedence and associated one with each of the lines of the second group, means for rendering inoperative the connection-determining devices of 30 busy lines, means for rendering that one of the connection-determining devices associated with idle lines which is first in precedence operative when a connection is to be made and then only and means for preventing 35 the operation of such connection-determining devices of idle lines as are lower in the order of precedence.

3. The combination of a group of electrical lines, a second group of lines, a number 40 of connection-determining devices arranged in a definite order of precedence and associated one with each of the lines of the second group, means for controlling each device both from its associated outgoing line 45 and from such devices as have precedence over it, means for rendering inoperative the connection-determining devices of busy lines and means for rendering that one of the connection-determining devices associated with 50 idle lines which is first in precedence operative when a connection is to be made and then only.

4. The combination of a group of electrical lines, a group of outgoing lines, a group 55 of incoming lines, a connection-determining device associated jointly with one of the outgoing lines and with one of the incoming lines, means for rendering the device inoperative when either its outgoing or its incoming line is engaged and means for rendering the device operative to connect one of the first mentioned group of lines either to its outgoing or to its incoming line when such outgoing and incoming lines are idle.

5. The combination of a group of electri-

cal lines, a group of outgoing lines, a group of incoming lines, a plurality of connection-determining devices arranged in a definite order of precedence and each associated jointly with one of the outgoing lines and 70 with one of the incoming lines, means for rendering inoperative any device when either its outgoing or incoming line is engaged, means for rendering operative the first connection-determining device of which both 75 the outgoing and incoming lines are idle and means for preventing the operation of such devices as are lower in the order of precedence than such first device.

6. The combination of a group of lines, 80 a source of current, a group of outgoing lines, a number of connecting relays each of which is associated both with a line of the first group and with an outgoing line, a current-connecting relay associated with 85 each line of the first mentioned group and adapted to connect to the source of current all the connecting relays associated with its line, a connection-determining relay associated with each outgoing line and adapted with 90 to complete the circuit of any of the connecting relays associated with its line, means for rendering inoperative the connection-determining relays of busy outgoing lines and means for rendering operative the connection-determining relay of one idle outgoing line and one only.

7. The combination of a group of lines, a source of current, a group of outgoing lines, a group of incoming lines, a number 100 of connecting relays each of which is associated with a line of the first group, with an outgoing line and with an incoming line, a current-connecting relay associated with each line of the first-mentioned group and 105 adapted to connect to the source of current all the connecting relays associated with its line, a number of connection-determining relays each associated both with an outgoing and with an incoming line and adapted to 110 complete the circuit of any of the connecting relays associated with its lines, means for rendering inoperative the connection-determining relays of busy outgoing or incoming lines and means for rendering operative the connection-determining relay of 115 one idle outgoing or incoming line and one only.

8. The combination of a group of lines, a source of current, a group of outgoing lines, 120 a number of connecting relays each of which is associated both with a line of the first group and with an outgoing line, a current-connecting relay associated with each line of the first-mentioned group and adapted to 125 connect to the source of current all the connecting relays associated with its line, a number of connection-determining relays arranged in a definite order of precedence, associated one with each of the outgoing lines 130

and adapted to complete the circuit of any of the connecting relays associated with its line, means for rendering inoperative the connection-determining relays of busy outgoing lines, means for rendering operative that one of the connection-determining relays associated with idle lines which is first in precedence and means for preventing the operation of such connection-determining 10 relays of idle lines as are lower in the order of precedence.

9. The combination of a group of lines, a source of current, a group of outgoing lines, a group of incoming lines, a number 15 of connecting relays each of which is associated with a line of the first group, with an outgoing line and with an incoming line, a current-connecting relay associated with each line of the first mentioned group and 20 adapted to connect to the source of current all the connecting relays associated with its line, a number of connection-determining relays arranged in a definite order of precedence, associated one with each of the outgoing

lines, means for rendering inoperative the connection-determining relay of any busy outgoing or incoming line, means for rendering operative that one of the connection-determining relays associated with idle lines which is first in precedence and means for preventing the operation of such connection-determining relays of idle lines as are lower 35 in the order of precedence.

10. The combination of a group of electrical lines, a second group of lines, a connection-determining device associated with each of the lines of the second group, and means 40 for momentarily rendering operative the connection-determining device of one idle line and one only to bring about a connection.

In testimony that I claim the foregoing 45 as my invention, I have signed my name this 8th day of December 1916.

LEONARD CHARLES BYGRAVE.
